CLAIM

The ornamental design for a timing measuring instrument housing or similar article, as shown and described.

DESCRIPTION

FIG. 1 is a front elevational view of a timing measuring instrument or similar article showing our new design;

FIG. 2 is a top plan view thereof;

FIG. 3 is a right elevational view thereof;

FIG. 4 is a rear elevational view thereof;

FIG. 5 is a bottom plan view thereof;

FIG. 6 is a cross-sectional view as taken from line 6—6

FIG. 1; and

FIG. 7 is a left side elevational view thereof.
